UNITED STATES PATENT OFFICE

WILLIAM J. YOUNG, OF PEABODY, MASSACHUSETTS, ASSIGNOR TO W. J. YOUNG MACHINERY COMPANY, OF LYNN, MASSACHUSETTS, A CORPORATION OF MASSACHUSETTS

MACHINE FOR MAKING COUNTERS

Application filed September 11, 1928. Serial No. 305,202.

The present invention relates to machines for making counters.

The usual process for making counters comprises a number of separate operations.

5 Counters are first skived in a skiving machine and are then passed through a corrugating machine for corrugating the margins along the edge, after which they are presented to a counter rolling or "clam-shell-
10 ing" machine, so-called, for rolling them into the desired shape. It is also common practice to pass the counters after skiving and before rolling through a marking machine for printing the desired characters thereon.

15 The skiving machine may be fed by hand or automatically and according to the usual practice, the counters after being skived, are fed by hand separately to the marking devices and to the corrugating and rolling machines. According to this method, the at-
20 tendance of a separate operator for each of the several machines is ordinarily required.

The object of the present invention is to provide a machine for automatically forming 25 a completed counter without the necessity for attendance of more than one operator and to this end the invention consists in the counter making machine hereinafter described and particularly defined in the claims.

30 In the accompanying drawings, Fig. 1 is a plan view of so much of the preferred form of the machine as is necessary to understand the present invention; Fig. 2 is an elevation, partly in section, of the machine shown in Fig. 35 1, taken on line 2—2 of Fig. 1 and looking in the direction of the arrows; and Fig. 3 is a side elevation of the conveyor looking in the opposite direction.

The illustrated embodiment of the invention 40 comprises generally a counter skiving mechanism indicated at 4, a counter rolling or clam-shelling mechanism 6 which also includes the corrugating mechanism, a printing mechanism 8, and a conveying mechanism 10 for conveying the skived counters from the skiving mechanism to the printer and from the printer to the rolling mechanism.

The skiving mechanism 4 has a frame 12 within which are mounted the usual rolls 14 for presenting the blank to the skiving knife.

The rolls are driven in the usual manner from a train of gears suitably connected with the main driving shaft 16. The shaft 16 has fixed thereon a gear 18 which drives a knurled roll 20 through a gear 22 on a shaft 24. The shaft 24 also carries a gear 26 which meshes with a gear 28 on a shaft 30, a roll 32 being also secured to the shaft.

The skived blanks leaving the skiving mechanism enter the bite of the rolls 20 and 32 and are thereby moved along a table 34 forming a part of the conveying mechanism 10. A plate 36 secured to a bar 38 extending across the delivery end of the skiving mechanism acts to prevent upward movement of the blanks and to guide them to the bite of the rolls. It will be seen that the rolls 20 and 32 are revolved in opposite directions in a manner to advance the blanks along the conveyor table.

The shaft 30 is journaled in a bracket 40 and is formed with yoke ends 42 pivoted on a shaft 44 secured in ears 46 upstanding from opposite sides of the table. A tension spring 48 secured between the bracket and the conveyor frame serves to hold the rolls 20 and 32 in proximity but permits them to separate sufficiently to let a blank pass between them. The movement between the rolls sufficient to accommodate the blank is not great enough to take the gears 26 and 28 out of mesh. The axis of the knurled roller 20, as shown in Fig. 2, is below the upper surface of the table 34 and the bite of the two rolls extends slightly above the table. The conveyor table 34 has a side flange 50 which is secured by brackets 52 and 54 to the frame 12 of the skiver.

After passing the rolls 20 and 32, the blank is next presented to a pair of feeding rolls indicated at 56 and 58. The lower feeding roll 56 protrudes slightly through an opening in the table and is adapted to engage the roll 58 when a blank is not being fed thereby. The rolls 56 and 58 are journaled on shafts 60 and 62 respectively upon which are secured gears 64 and 66 which mesh with each other. The gear 64 is driven by a gear 68 on a stud 70 which in turn is driven by a gear 72 meshing with another gear 74 on the stud 76, the studs 70 and 76 being mounted in the bracket

54. The gear 74 is driven by a gear 78 secured to the main shaft 16 of the skiving machine. It will be seen that by this train of gears, the rolls 64 and 66 are rotated in opposite directions and in a manner to advance the counters over the table toward the rolling device. The shaft 62 which carries the upper roll 58 and the gear 66 is journaled in a yoke shaped bracket 80 which pivots on the shaft 44, the rolls being urged toward each other by a spring 82 connected between the bracket and the frame.

10 Additional pairs of rolls 84 and 86 similar to the rolls 56 and 58, are provided at various points along the conveyor table. 15 These rolls are yieldingly mounted in a similar fashion to the mounting of the rolls 56 and 58. All of the rolls of the conveyor are driven by the gear 64 which meshes with a 20 large gear 88, this latter gear connecting through gears 90, 92, 94, 96 and 98 to drive the rolls as shown in Fig. 3. The large gears 88, 92 and 96 are mounted in studs 99 which are secured to the conveyor frame. The spacing 25 between successive pairs of rolls is such that the blank is engaged by one pair before being released by the preceding pair.

When a printing operation is not desired, the gear 90 may be utilized to operate a set 30 of rolls similar to the pairs of rolls 86. In the illustrated embodiment of the invention, however, this gear is employed for the purpose of effecting a printing operation. The gear 90 drives a roll 100 similar to the roll 56. Above 35 the roll 100 is a printing roll 102 which carries suitable type for impressing any desired characters on the blanks. The printing roll 102 is secured to a shaft 104 which is rotated by a gear 106 meshing with the gear 90. The 40 roll 102 is mounted in a pivoted bracket 108 to permit a slight relative movement between the rolls whereby the blank may pass between them.

The bracket 108 has upstanding arms 110 which are slotted at 112 to receive the inking roll shaft 114. A felt covered inking roll 115 is mounted on the shaft 114. A pair of tension springs 116 connected between the upper ends of the arms 110 and opposite sides 50 of the conveyor frame serve to press the printing roll against the blank. An ink reservoir 118 is mounted on a bracket 120 secured to the conveyor frame and is adapted to supply a uniform quantity of ink to the roll 115. 55 The ink is uniformly distributed over the felt roll 116 by means of a piece of felt 122 secured at one end to the bracket 120 and pressing at the other end against the roll 115.

At the left hand end of the conveyor, as 60 shown in Fig. 2, the blanks enter the mouth 124 of the clam-shelling apparatus 6. In order to prevent upward movement of the blanks over the top of the mouth 124, a flat plate 126 extends across the conveyor above 65 the table. The plate is secured to a bar 128

which is secured at opposite ends to the sides of the conveyor. The plate extends slightly over the end of the conveyor and above the mouth 124. After being guided by the mouth 124 into the rolling machine, the blank is engaged by the corrugating rolls 130 which engage and corrugate the surface of the blank adjacent one margin or edge in the well known manner, and are passed thence into the rolling machine for the usual clam-shelling operation. The construction of the clam-shelling machine may be of any usual or preferred form.

70 The conveyor is provided with side guide plates 132 which extend close to the feeding rolls and serve to maintain the blanks in proper position as they are fed over the table. Each guide plate is attached to a slotted arm 134 which is secured to an ear 136 extending outwardly from the conveyor 75 frame.

According to the present invention, the blanks are fed to the skiving machine in any desired manner either by hand or by an automatic feeding device. They are automatically skived, corrugated, and rolled and when desired, they are also automatically printed or otherwise marked, being delivered from the clam-shelling machine in completely 90 rolled form. The only attendance required 95 is for the feeding of the blanks to the skiving machine.

While the present invention has been illustrated as embodied in a machine provided with a roll conveyor, it is obvious that the 100 invention is not limited to this specific arrangement but may include other and different forms of conveyor whether of the roll, belt, or some other type. Nor is it essential 105 that the corrugating mechanism be located adjacent the rolling mechanism as shown, since it may equally well be placed close to the skiving devices or at any desired point between these rolling and skiving mechanisms. If, as is sometimes the case, the marking of the counter is not desired, the printing mechanism may be omitted entirely.

110 Having thus described the invention, what is claimed is:

1. A machine for making counters having, in combination, a counter skiving device for skiving blanks in flat condition, a counter rolling device, and a conveyor for receiving the blanks in flat condition from the skiving device and delivering them flat to the rolling device.

2. A machine for making counters having, in combination, a counter skiving machine, a conveyor having rolls to engage blanks delivered from the skiving machine, additional rolls for advancing the blanks and engaging them prior to release thereof from the preceding rolls, and a counter rolling machine to receive the blanks from the conveyor.

125 3. A machine for making counters having,

in combination, a counter skiving machine, a counter rolling machine, a conveyor for receiving the blanks from the skiving machine and delivering them to the rolling machine, the conveyor comprising a plurality of sets of rolls to engage the blanks, one of the rolls comprising a printing roll, and means for inking the printing roll.

4. A machine for making counters having, in combination, a counter skiving machine, a counter rolling machine, a conveyor for receiving the blanks from the skiving machine and delivering them to the rolling machine, the conveyor comprising a plurality of sets of rolls to engage the blanks, and guides for guiding the blanks between the sets of rolls, one of the rolls comprising a printing roll, and means for inking the printing roll.

5. A machine for making counters having, in combination, a counter skiving device, a counter rolling device, a corrugating device, and conveyor mechanism for automatically passing the counters in flat condition from one device to another.

6. A machine for making counters having, in combination, a counter skiving device, a counter rolling device, a corrugating device and a printing device, both located intermediate the skiving and the rolling devices, and conveyor mechanism for automatically passing the counters from one device to another.

7. A machine for making counters having, in combination, a counter skiving machine, a counter rolling machine, and a conveyor having a series of driven rolls spaced in the line of the feed for engaging one face of the counter to advance it from the skiving to the rolling machine.

8. A machine for making counters having, in combination, a counter skiving machine, a counter rolling machine, and a conveyor having a pair of opposed rolls to receive the counter therebetween and advance it from the skiving to the rolling machine.

9. A machine for making counters having, in combination, a counter skiving machine, printing devices, and a conveyor driven from the skiving machine for conveying the counters in flat condition from the skiving machine to the printing devices and away from the printing devices.

10. A machine for making counters having, in combination, a counter skiving machine, a printing device, a counter rolling machine, and a conveyor connected to and driven from the skiving machine for advancing the counters in flat condition from the skiving machine to the printing device and from the printing device into position of presentation to the rolling machine.

In testimony whereof I have signed my name to this specification.

WILLIAM J. YOUNG.
